UNITED STATES PATENT OFFICE.

ROBERT SKELTON, OF DUBLIN, IRELAND.

CYCLING-SKIRT.

SPECIFICATION forming part of Letters Patent No. 632,592, dated September 5, 1899.

Application filed May 1, 1899. Serial No. 715,215. (No model.)

To all whom it may concern:

Be it known that I, ROBERT SKELTON, a subject of the Queen of Great Britain, residing at 40 and 41 Aungier street, Dublin, Ireland, 5 have invented certain new and useful Improvements in or Relating to Ladies' Cycling-Skirts, of which the following is a specification.

This invention has for its object a lady's cycling-skirt which can be worn also for walking 10 and like purposes.

To carry my invention into practice, I affix to the inside of an ordinary or improved skirt a cord or tape, which I rove through rings or like appliances, the free end of such cord or 15 tape being passed through a suitable opening for outside drawing to bring the back fairly close to the legs at the rear of the wearer for cycling and also a portion of the front, so that those parts fit loosely, like riding-breeches, 20 above the knees, leaving the lower part of the skirt somewhat full to fall well over the rear-wheel guard without the usual tendency for the lower front of the skirt to rise from the instep of the feet while pedaling, the seat of the 25 skirt remaining full and without drag or producing inconvenient tightness around the hips of the rider. The inner end of the running cord or tape is preferably attached to one eye of a double-eyed ring at or near the front, 30 said cord or tube being carried to the back, where it is roved through a plain ring or its equivalent back to the front ring, through 35 which it is roved, and from thence through the opening to the outside, where its free end can be drawn upon and secured to a button or other attachment.

By this invention a lady can step into her skirt and fasten it around her waist, and just previous to mounting the cycle she can draw 40 on the cord or tape and distribute the skirt equally from both sides inwardly and then take her seat, without the necessity of afterward rising from the pedals to adjust the garment.

45 My invention is represented on the annexed drawings.

Figure 1 is a face view of a double-holed ring for attachment to the inner front of a skirt and to which one end of a runner-cord is to be 50 attached; Fig. 2, an elevation of the double-holed ring of inner front of skirt, the runner-cord, and the plain ring which I attach to the

inner back of the skirt; Fig. 3, an elevation of skirt in an expanded form for ordinary walking or promenade purposes; Fig. 4, a sectional elevation of the skirt with the rear lower portion drawn toward the front by the runner-cord and leaving the seat portion very full, the front being also drawn somewhat close, such as to the body of a wearer, so that 55 the upper front may be well over or upon the knees and the lower part to fall close to the legs down to the insteps of the feet, the sides of the skirt, which are free, falling and lodging gracefully outside the rear-wheel guard 60 when the lady is sitting on her bicycle; Fig. 5, an elevation corresponding to Fig. 2, except that the ring affixed to the back of the skirt has a hook connection for the ready attachment to said back ring, the hook being part 70 of or as a link hook through which the cord or tape is roved.

In the accompanying drawings the letter A indicates a cord-guide secured to the inside of the center part of the front of the 75 skirt B, and D a cord-guide secured to the inside of the center part of rear E of the skirt. A cord-hole F is formed in the side of the skirt at a point in juxtaposition to the skirt-waistband. The cord-guides A and D and 80 cord-hole F are located at different heights or levels considerably above that part of the skirt which is normally on the line of the knees of the wearer. The cord-guide A is a double-hole ring, (best seen in Fig. 1,) and the 85 cord-guide D is preferably a plain single ring. (Best seen in Figs. 2 and 5.) A runner-cord C is secured at one end in one of the holes of the double-hole ring A and is led through plain ring D, affixed to inner rear portion E of skirt 90 at a lower level than the front ring A. The runner-cord C is led back from ring D and passed through the open eye of double ring A, from whence the free end of the cord C passes through the cord-hole F in the skirt, 95 which hole can be covered by a facing-piece G to give it the appearance of a pocket, the free end of the cord being secured to a button H or otherwise, as desired.

I have shown the cord-guide D as a plain 100 ring at the back inner portion of the skirt B for the passage of the cord, as at Fig. 3; but this guide may be otherwise constructed. A link hook I may be attached to the ring D for

the cord C to run through the eye D' of the hook I, as at Fig. 5.

It will be understood that the rings are so arranged to the front and rear of the skirt 5 that the runner-cord C has its position between the legs of the wearer, and when the cord is drawn the central rear portion of the skirt follows somewhat close up under the knees at the back, but leaves the back upper 10 or bustle portion J unaffected, which enables a lady wearing such a skirt to take her seat direct on a bicycle without the necessity of arranging her skirt afterward, as at present.

What I claim, and desire to secure by Letters Patent, is—

A cycling and walking dress-skirt having the cord-guide ring D secured at the rear directly below the bustle portion, the cord-guide ring A having two eyes or holes and secured

to the center of the front, the cord-hole F at 20 one side near the waistband, and the continuous, single cord C secured at one end in one of the eyes or holes of the front ring, passing back loosely through the rear ring, thence passing forward through the other eye or hole 25 of the front ring and thence ascending to and through said cord-hole, all as shown, whereby the central rear part of the skirt above the knees is drawn forward, and a central front part below the abdomen is drawn rearward, 30 by pulling said cord.

In testimony whereof I have hereunto set my hand in presence of two subscribing witnesses.

ROBERT SKELTON.
